REAR DOOR LOCK FOR VEHICLES

Augustine G. Langford, St. Paul, Minn.

Application December 17, 1938, Serial No. 246,266

8 Claims. (Cl. 292—182)

My invention relates to an improvement in rear door lock for vehicles, wherein it is desired to provide a safety lock operable to prevent the accidental opening of the rear doors of a passenger vehicle or other vehicle of the four door type.

During the past few years, numerous accidents have been caused by the accidental opening of the rear doors of vehicles while the same are in motion. Probably the majority of these accidents are caused by children in the rear seat of the vehicle playing with, or pushing against, the door latch of the rear door. As most of the vehicles of the four door type are constructed so that the rear doors are hinged at the back, any slight opening of the rear door causes the wind to catch the door and jerk it open, pulling outwardly anyone grasping the door latch. Even if the latch handle is not being held, the sudden opening of the door will cause a person leaning against the door to fall out. Furthermore, the increase in air resistance caused on one side of the vehicle by the sudden opening of the door often causes a person driving the vehicle to lose control thereover.

Attempts have previously been made to provide safety locks for the rear doors of cars. Most of these locks, however, have been costly and complicated to manufacture, and expensive to install. Some of these former devices make necessary a special formation of the door edges, so that the locks cannot be applied after the car has been manufactured.

It is the object of the present invention to construct a safety door lock for car rear doors which is extremely inexpensive to manufacture, which can be applied easily, and which can be added as an appliance to the car as manufactured, or may be added later at virtually no extra cost to the purchaser.

It is an object of my invention to provide a safety door lock for rear vehicle doors of a type in which the rear door will be effectively locked as long as the front door is in closed position. The opening of the front door of the vehicle acts to automatically release the safety lock and will permit the rear door to be opened in the usual manner. Thus, in parking the car, it is only necessary to lock the front doors, for as long as these doors are closed the rear doors cannot be opened, resulting in a considerable saving in time.

It is a purpose of my invention to provide a safety lock for rear car doors which will permit the rear door to be closed after the front door has been closed. Injury to the door, or to the lock, is thus prevented in case the rear door is closed after the front door. The rear door, once opened, can be closed any time.

It is an added feature of my invention that the

lock may be easily and quickly set in inoperative position. Thus, without removing the lock, it may be adjusted so that it will be inoperative when desired. With this provision, it is possible to use the lock when children are carried in the back seat and to hold the lock inoperative when older persons are transported.

It is also a feature of my invention that my lock is adjustable to fit virtually any make or type of car having four doors. Because of this, it is not necessary to provide a different size and shape of lock for every make and model of car manufactured.

These and other objects and novel features of my invention will be more clearly and fully set forth in the following specification and claims.

In the drawing forming a part of my specification:

Figure 1 is a perspective view of a car embodying my lock. 26

Figure 2 is a diagrammatic cross-sectional view through a door post between the front and rear doors showing the relationship of the doors thereto, as indicated by line 2—2 of Figure 1.

Figure 3 is a view similar to Figure 2 showing the front door open to release the safety lock 25 from engaging the rear door.

Figure 4 is a section similar to Figure 3, showing the lock in inoperative position.

Figure 5 is a perspective view of the lock itself, showing the relationship of the parts. 30

Figure 6 is a perspective view of the lock with the catch for making the lock inoperative being changed from operative to inoperative position, or vice versa.

Figure 7 is a plan view of the forward portion 35 of the locking bolt.

Figure 8 is a perspective view of the catch capable of rendering the lock operable or inoperative.

Figure 9 is a perspective view of the spring 40 supporting and actuating the locking bolt.

Figure 10 is a perspective view of a slightly different form of actuating spring.

Figure 11 is another modified form of actuating spring. 45

Figure 12 is a perspective view of the form of catch rendering the lock operable or inoperative used in conjunction with the spring of Figure 11.

The safety lock A is designed to extend through the post 18 between the front door 11 and the rear door 12 of the automobile B. The lock is completely supported by the post 18, and is operated by the front door 11 to engage the rear door 12. 50

The locking bolt 13 is adapted to engage the edge of a recess 14 in the rear door 12 in case the usual door latch is actuated, to prevent the same from swinging outwardly. The locking bolt 13 is supported by a spring strip 15 and a spring 60

catch 16. The spring strip 15 is secured to the post 10 by any suitable means such as the screw 17, and the spring catch 16 is pivoted to the spring strip 15. The bolt 13 extends through aligned apertures 18 transversely through the post 10, from the edge thereof adjacent the front door 11 to the edge adjacent the rear door 12.

The bolt 13 comprises two parts threaded together so as to be adjustable in length. The female portion 19 includes a socket portion 20 of enlarged diameter which is hollow axially and is internally threaded, and a locking shank 21 of smaller diameter. The end of the shank 21 is bevelled at 22 to permit actuation by the rear door if the rear door is closed after the front door has been closed. The male portion 23 of the bolt 13 is threaded to fit into the socket portion 20, and is provided with three sets of opposed transverse slots. Two of these pairs of slots, 24 and 25, extend vertically when the bolt 13 is in place to engage the spring catch 16 in a manner which will be later described. The third pair of opposed slots 26 are designed to receive the end of the spring strip 15. A lock nut 27 is provided on the threaded portion 23 of the bolt, to hold the male and female portions of the bolt 13 in proper adjusted relationship.

The spring strip 15 is bifurcated at each end. The central slot 28 at one end thereof is designed to accommodate the screw 17 extending into the post 10. The central slot 28 is preferable to an aperture through the spring strip, as it permits adjustment longitudinally of the spring strip. The slot 29 in the other end of the spring strip 15 is of substantially the same width as the body portion of the threaded bolt portion 23 between the opposed slots 26. The fingers on either side of the slot 29 engage in the slots 26 and hold this bolt adjustable longitudinally of the spring strip 15, but non-rotatable with respect thereto. When the screw 17 is in place, the bolt 13 is normally held retracted or drawn forwardly by the spring strip; the intermediate forwardly bulging loop portion 30 of the spring strip holding the bolt in this forward position.

The spring catch 16 is pivotally connected at one end to the spring strip 15. In the form shown, an ear 31 on the end of the catch 16 extends through an aperture 32 in the strip 15. This ear 31 is bent forwardly at right angles to the body of the catch, and then bent parallel to the catch, providing a portion 33 designed to overlie the body of the spring strip 15. The aperture 32 is of sufficient size to permit the catch 16 to pivot a desired extent with respect to the spring 15.

The catch 16 is provided with a slot 34 extending into the body of the same from the lower edge thereof. This slot 34 is of proper width to engage in the opposed slots 24 or 25. When engaged in the slots 25, the catch 16 does not affect the operation of bolt 13. When engaged in the slots 24, however, the bolt 13 is prevented from sliding into engagement with the rear door 12. A lip 35 on the end of the catch 16 enables the catch to be engaged for operation.

In applying the lock A to the car B, aligned openings 18 are formed through the post 10, and an opening or recess 14 in registry therewith is formed in the rear door 12. The bolt 13 is assembled and attached to the spring strip 15 and catch 16 as shown in Figure 5 of the drawing. The bolt 13 is inserted through the openings 18 in the post 10, and the screw 17 is screwed into the post 10, the screw being positioned in the

slot 28. The screw 17 has its axis on substantially the same horizontal plane as the axes of the holes 18.

The length of the bolt 13 is adjusted so that, when the front door 11 is open, the tapered end 5 or bevelled end 22 is in close proximity to the aperture or recess 14 in the rear door 12, but is not actually extending into the same. It will then be found that as the front door is closed, the edge 36 thereof will engage the central loop 10 portion 30 of the spring strip 15, flexing the spring rearwardly, and moving the bolt 13 rearwardly. If the rear door 12 is closed, the bolt 13 will then project into the aperture 14. If, on the other hand, the rear door 12 is not closed, the 15 bolt 13 will be extended rearwardly so that the bevelled end 22 thereof is in the path of the inner corner 37 and forward edge 38 of the rear door 12. Accordingly, if the rear door 12 is closed while the bolt is in this position, the bevelled 20 surface 22 will engage the corner 37 and edge 38, sliding the bolt 13 forwardly and flexing the spring strip 15 until the rear bevelled end of the bolt drops into the recess 14. When thus engaged, any attempt to open the rear door will 25 cause the locking shank 21 to engage the inner edge of the recess 14. Obviously, the side of the shank 21 opposite the bevelled surface 22 will engage the recess edge.

To release the lock, the front door 11 is opened 30 slightly, relieving pressure against the spring strip 15 which then assumes its normal position, pulling the bolt 13 forwardly out of the recess 14. Thus, when the lock A is in operation, the rear doors 12 can be opened only when the front 35 doors are open.

In some instances, it is desired to open the rear doors without opening the front doors. In order to permit such operation when desired, the lip 35 is engaged, and the inner end of the spring 40 catch 16 is pivoted upwardly as illustrated in Figure 6. This action releases the spring catch 16 from engagement with the opposed slots 25. The spring catch 16 is then flexed rearwardly into registry with the pair of opposed slots 24, 45 and pivoted downwardly, the body of the threaded portion 23 of the bolt 13 between the slots 24 being engaged in the slot 34 of the catch 16. When thus engaged, the engagement of the loop portion 30 of the spring 15 with the rear edge 50 36 of the front door 11 will cause the catch 15 to be pressed against the forward edge 39 of the post 10. Further rearward movement of the bolt 13 is prevented, and the closing of the front door 11 will merely flex the spring strip 15. The bolt 55 13 will thus be held out of the recess 14 in the rear door 12.

While the position of the bolt 13 when in engagement with the rear door 12 is shown in full lines in Figure 2 of the drawing, this figure also 60 shows in dotted outline the manner in which the bolt may be moved forward while the front door 11 is held closed. This dotted line position would be assumed during the closing of the rear door 12 after the front door 11 had been closed. This 65 dotted line position of the spring strip 15 and bolt 13 would also be assumed after the front door 11 is closed if the catch 16 were in engagement with the slots 24 rather than the slots 25. The position of the parts in Figure 4 shows the catch 70 16 engaging the slots 24 while the front door 11 is open.

From an observation of Figure 2, it will be noted that when the front door 11 is closed, the bolt 13 will, in most installations, be flexed against 75

the outer edge of the rear aperture 18 in the post

10. This engagement of the bolt 13 with the post 10 under spring tension will prevent rattling of the bolt 13 in the relatively large apertures 18.

5. If the recess 14 is in direct registry with the openings 18, a slight outward movement of the rear door 12 is permitted if this door is unlatched. This is often advantageous, as the looseness of the locking engagement of the rear door will im-

10. mediately indicate that the regular door latch is disengaged. Furthermore, if resilient gaskets surround the door, these gaskets might otherwise cause a binding between the edge of the aperture 14 and the bolt 13 which will prevent the spring strip 15 from readily retracting the bolt when the front door is opened. If desired, however, the

15. recess 14 may be formed to prevent outward movement of the rear door to any noticeable degree.

20. In Figure 10 of the drawing I have disclosed a type of spring strip which can be used in place of the spring strip 15. This spring 40 is formed with a loop portion 41, and bifurcated ends 42 and 43 both of which extend in the same direction. This construction permits greater spring action, but cannot be used on every type of car construction, as more space is required between the post 10 and the front door 11 than is available in some types of cars. Such a spring, however,

25. is advantageous for use where sufficient space is found.

Virtually the reverse of the spring shown in Figure 10 is shown in Figure 11. This construction simulates that of Figure 9, but one end 46 is bent inwardly and slotted at 47 to accommodate the fastening screw 17. The other end of the spring 48 is slotted at 49 to accommodate the end of the portion 23 of bolt 13, fitting in the slots 26. The central loop portion 50 provides the spring engagement with the front door 11. An aperture 51 is formed in the front of the spring to admit the head of screw 17. A flange 52 is bent outwardly from the end 46, and is slotted to provide a hinge joint with the spring catch 53 shown in Figure 12.

45. The catch 53 is similar to the catch 16, but has an ear 54 bent to engage through the slot 55 in the flange 52. If desired, the tongue or ear may be on the spring 48, and the hole may be formed in the catch 53, forming the pivotal joint.

50. The bolt 13 is shown adjustable, to fit virtually any width of post 10. The bolts 13 may be made long enough to fit any post 10; and if thinner posts are encountered, the portion 23 may be cut off to make the bolt shorter. The spring catch, and its function, may also be omitted if desired. This catch, however, is valuable in providing an additional support for the bolt 13, to prevent any looseness between the spring and the bolt. It 55. will be seen that the lock A will function properly regardless of whether the front door 11 is pivoted at the front or at the back, as the spring 15, 48 or 48 will flex when the door 11 is closed in either instance. The spring does not act as a cam, but as a spring to resiliently urge the bolt 13 rearwardly.

70. I have described what I believe to be the preferred constructions of my device. However, I desire to make it known that obvious changes may be made within the scope of the following claims, without departing from the spirit of my invention.

I claim:

1. In combination with a vehicle having a front door, a rear door, and an intermediate post, a bolt slidably engageable and disengageable with said rear door, a resilient means securing said bolt to said post, said resilient means being engageable with said front door to operate said bolt into engagement with said rear door.

2. In combination with a pair of oppositely hinged doors and a center post, a bolt slidably engageable and disengageable with one of said doors, spring means connecting said bolt to said post, said spring means engaging said other door and operable under this engagement to resiliently urge said bolt into engagement with said one door.

3. In combination with a pair of oppositely hinged doors and a center post, a bolt slidably mounted on said post engageable and disengageable with one of said doors, and a spring means connecting said bolt to said post, said spring formed to engage the other of said doors at a point spaced from the connections with said post and said bolt to resiliently force said bolt into engagement with said one door.

4. In combination with a pair of oppositely hinged doors and a center post, a bolt movably mounted on said post engageable and disengageable with one of said doors, means for adjusting the length of said bolt, and spring means connecting one end of said bolt to said post, said spring means engageable with said other door in the closing of said other door to urge said bolt resiliently into engagement with said one door.

5. In combination with a pair of oppositely hinged doors and a center post, a bolt movably mounted on said post for engagement and disengagement with one of said doors, means on said bolt engageable with the other of said doors to urge said bolt into engagement with said one door, notch means in said bolt and means engageable with said notch means in said bolt to hold said bolt from movement by said other door.

6. In combination with a pair of oppositely hinged doors and a center post, a bolt movably mounted on said center post for engagement with one of said doors, means on said bolt overlying a portion of the exterior surface of said center post engageable with the other of said doors for movement thereby, said means forming a resilient support for said bolt, and means for locking said bolt from movement by said other door.

7. In combination with a pair of oppositely hinged doors and a center post, a rigid bolt movably mounted on said center post and projecting from both sides thereof engageable in one position with one of said doors, means resiliently connecting one end of said bolt to said post, said resiliently connecting means engageable with said other door for resiliently urging said bolt into engagement with said one door, and means for locking said bolt from movement.

8. In combination with a pair of oppositely hinged doors and a center post, a bolt movably mounted on said center post engageable in one position with one of said doors, resilient means on one end of said bolt engageable with the other of said doors and movable thereby to resiliently urge said bolt into engagement with said one door, and means engageable with said one end of said bolt to prevent movement into engagement with said one door.

AUGUSTINE G. LANGFORD.
